ROTARY IMPACT TOOL

Ernest H. Shaff, Spring Lake, Mich., assignor to
 Keller Tool Company, Grand Haven, Mich., a
 corporation of Michigan

Application May 20, 1947, Serial No. 749,280

14 Claims. (Cl. 192—096)

1

The invention relates to rotary impact tools of the type intended for use as nut runners, impact wrenches and the like, and the general aim of the invention is to provide a rotary impact tool embodying a disengageable clutch mechanism characterized by extreme simplicity in construction, low cost of manufacture and efficiency in operation.

The invention concerns especially a rotary impact tool utilizing an air motor, and the primary object of the invention is to provide in such a tool, fluid pressure operated means for effecting engagement and disengagement of the clutch mechanism.

A further object is to provide an impact clutch for tools of the character set forth having rotary anvil and hammer elements and embodying pressure fluid actuated means and control means therefor operative to impart rapidly recurring pressure impulses to the hammer element to effect the engagement and disengagement thereof with respect to the anvil element.

Another object is to provide in an impact clutch having a rotary anvil element, a motor driven hammer element movable into and out of driving engagement with the anvil element by pressure fluid actuated means including a pressure chamber and valve means whereby fluid pressure is admitted to the chamber during the rotation of the hammer element and is exhausted from the chamber upon interruption of rotation of the anvil element.

The objects of the invention thus generally set forth, together with other and ancillary advantages, are attained by the construction and arrangement shown by way of illustration in the accompanying drawings, in which:

Figure 1 is a fragmentary vertical sectional view through a rotary impact tool embodying my invention.

Fig. 2 is a transverse sectional view taken approximately in the plane of line 2—2 of Fig. 1.

Fig. 3 is a fragmentary horizontal sectional view taken approximately in the plane of line 3—3 of Fig. 1.

Fig. 4 is a cross sectional view on line 4—4 of Fig. 1.

Fig. 5 is an exploded view in perspective of certain of the elements of the clutch mechanism.

Fig. 6 is a transverse sectional view in the plane of line 6—6 of Fig. 1.

Fig. 7 is a similar view in the plane of line 7—7 of Fig. 3.

I have herein shown for purposes of illustration an impact tool having a rotary air motor 10

2

enclosed within the rear section 11 of a tool casing having a forward section 12 enclosing a clutch mechanism generally designated 13. The two sections of the casing are screw threaded together 5 and the rear section is equipped with a handle 14 providing an air supply chamber 15 from which air is delivered to the motor under the control of a throttle valve 16.

The motor 10 may be of any suitable or preferred construction. That herein shown is of the type disclosed in my prior Patent No. 2,099,280, dated November 16, 1937. It consists in general of a cylinder 17 enclosing a rotor 18 with radial vanes or blades 19. A reversing valve 20 controls the direction of rotation of the motor.

The clutch mechanism comprises an anvil element 21 mounted for rotation in the forward section 12 of the casing, and a hammer element 22 mounted for rotary and axial movement with respect to the anvil element. The latter is equipped with a plurality of jaws 23 providing abrupt shoulders or faces 24 lying within substantially radial planes extending longitudinally of the axis of the tool. Complementary jaws 25 are formed on the hammer element in opposed relation to the anvil element and provide similarly disposed shoulders or faces 26 for coaction with the faces 24 of the jaws 23. The hammer element is mounted upon a stub shaft 27 having a bearing in the anvil element 21, and a coiled compression spring 28 encircles the shaft in interposed relation to the anvil and hammer elements 30 so as to tend to effect a separation of the two elements.

35 In accordance with my invention, engagement and disengagement of the hammer element with respect to the anvil element is accomplished by fluid pressure means operative to impart intermittent pressure impulses to the hammer element 40 22 to produce a succession of blows on the anvil. In the present preferred embodiment of the invention such fluid pressure operated means comprises a pressure chamber 29 having one wall or pressure area formed by the hammer element, 45 and an opposed wall formed by a diaphragm 30 of flexible and resilient material such as rubber. To effect the engagement and disengagement of the hammer element from the anvil, fluid pressure is admitted to the chamber 29 while the hammer is rotating and is periodically exhausted therefrom when the anvil and therefore the hammer are interrupted in their rotation. In the present instance pressure fluid is constantly delivered to the chamber and is exhausted therefrom under the control of a valve device actuated

automatically as an incident to the interruption in the rotation of the anvil element by the work being operated upon. As shown, the valve device has a part in the form of a disk 31 driven by the motor, and a second part in the form of a circular flange 32 (Fig. 3) rigid with the hammer element, the arrangement being such that when the hammer element is interrupted in its rotation by engagement with the anvil, the parts of the valve device are relatively shifted so as to exhaust fluid pressure from the chamber.

Referring now more particularly to the construction and arrangement herein employed in providing the pressure chamber 29, the motor rotor 18 is formed with a forward axial extension 33 of hexagonal cross section (Fig. 2), which is received within a sleeve 34 forming part of a driver 35 and having a hexagonal socket 36 for receiving the rotor extension 33. The hammer element is generally in the form of a disk from the periphery of which the flange 32 projects rearwardly so as to form the outer peripheral wall of the chamber 29. Within this flange is snugly fitted a ring 37 to the inner peripheral surface of which is bounded the outer peripheral edge of the diaphragm 30. The inner edge of the diaphragm in turn is bounded to the sleeve 34 so as to form the rear wall of the pressure chamber 29. Rigid with the sleeve 34 of the driver 35 is a hexagonal head 38 extending through a complementally shaped hole 39 in the valve disk 31 and into a circular recess 39a in the hammer element. The stub shaft 27 is preferably secured to the driver head 38 as by means of a pin 40.

To supply air under pressure to the chamber 29, the motor rotor 18 has an axial passage 41 communicating with a chamber 42 formed in the rear casing section 11 and supplied with air by way of a port 43 in either position of the reversing valve 20. The passage 41 extends through the rotor extension 33 and opens into a recess 44 in the driver head 38, said recess having radial ports 45 opening into the pressure chamber 29. Thus fluid pressure is constantly admitted to the chamber 29.

It will be seen that the valve disk 31 is splined upon the head 38 of the driver 35 so that in the operation of the rotor, the valve disk is positively driven. At the same time it is capable of moving axially with the hammer and with respect to the driver. However, the extent of relative rotation of the valve disk relative to the hammer is limited by means of a pair of pins 46 carried by the hammer element and projecting into radial slots 47 in the valve disk, the slots being of a width somewhat greater than the diameter of the pins so as to permit of a limited relative rotational movement between the valve disk and the hammer element. Such relative rotational movement is utilized to permit the exhaust of air from the chamber. For this purpose, the valve disk is provided in the present instance with a series of radial ports 48 coaxing with another series of ports 49 in the flange 32 of the hammer element. As shown in Fig. 4, there are two sets of the ports 48 and 49, with three ports 48 in each set and four ports 49. In the normal relationship of the parts (Fig. 4), the ports 48 are disposed between adjacent ports 49 and, depending upon the direction of rotation of the driver, when the hammer element is interrupted in its rotation by engagement with the anvil element, the ports 48 move into register with the ports 49. In this connection, it will be

observed that the pins 46 and their coaxing notches 47 properly limit the extent of relative shifting movement of the two parts of the valve device.

5 In the operation of the tool, fluid under pressure is constantly admitted to the pressure chamber 29 whenever the throttle valve 16 is operated to supply air to the motor. Thus, air flows from the chamber 15 past the valve 16 and reversing valve 20 into the chamber 42, and thence through the passage 41 to the recess 44 of the driver from which it passes to the chamber through the ports 45.

10 In the rotation of the rotor, the hammer element is driven by the diaphragm 30 by reason of the bonded connection between the driver 35 and the hammer element. In such rotation, the hammer element occupies a position with respect to the valve disk 31 shown in Fig. 4 so that the escape of fluid pressure from the chamber 29 is cut off. The result is that the hammer element is slid axially flexing the diaphragm substantially as shown in Fig. 3, to carry the driving jaws 25 of the hammer element into engagement 15 with the jaws 23 of the anvil element. This relationship of the parts continues during the nut running or equivalent operation, but when the anvil element is interrupted in its rotation, the hammer element is likewise interrupted, whereupon the valve disk 31 continues its rotation with the driver, carrying the ports 48 into register with the ports 49 so as to vent the chamber 29 and permit the exhaust of fluid pressure from the chamber. The exhausting fluid pressure 20 enters the forward housing section 12 from which it passes rearwardly through one or more ports 48 in one of the end plates of the motor, and thence through radial ports 49, an annular recess 50 and one or more exhaust ports 51.

25 30 35 40 Upon the exhaust of fluid from the chamber 29, pressure within the chamber is quickly relieved to permit the diaphragm, assisted by the spring 28, to disengage the hammer element from the anvil element. In the relative rotational movement of the driver with respect to the hammer element incident to the interruption of the rotation of the latter, the diaphragm 30 yields in a circumferential direction, and because of the resiliency of this diaphragm, the parts are restored, upon disengagement of the hammer element from the anvil element, to normal relationship, thus closing the ports 49. Thus pressure fluid again builds up in the chamber 49, forcing the hammer element into engagement 45 with the anvil element and the operation is repeated.

45 50 55 60 It will of course be understood that in the absence of valve means controlling the inlet ports 45, the outlet ports 48, 49 are proportioned with respect to the inlet ports 45 as to permit of the escape of pressure fluid from the chamber much faster than it is supplied to the chamber. Thus the valve device is effective to cause intermittent pressure impulses to be transmitted to the hammer as an incident to the interruption of rotation of the hammer by the anvil.

I claim as my invention:

65 70 75 80 85 90 95 1. A rotary impact tool comprising, in combination, a fluid pressure operated motor, valve means controlling the supply of pressure fluid to the motor, a rotary anvil, an axially shiftable hammer rotatable relative to the anvil, a driver for said hammer connected with said motor for rotation thereby, and means for effecting the engagement and disengagement of the

hammer with respect to the anvil including a pressure chamber, a passage leading to said chamber, said valve means controlling the supply of pressure fluid to the motor also controlling the supply of pressure fluid to said passage, and a valve device comprising a part carried by said hammer and a coacting part yieldably held in a normal position with respect to the hammer and shiftable relative to the hammer by said driver when the rotation of the hammer is interrupted by engagement with the anvil, said valve parts being operative upon interruption of rotation of the hammer to permit the exhaust of pressure fluid from the pressure chamber.

2. In a rotary impact tool, a clutch mechanism comprising, in combination, a rotary anvil, a hammer rotatable relative to the anvil and shiftable axially into and out of driving engagement with the anvil, a driver, and means for effecting the engagement and disengagement of the hammer element with respect to the anvil comprising a diaphragm of resilient material connecting the driver with said hammer and coacting therewith to form a pressure chamber, an air supply passage, means for supplying air under pressure to said chamber during the rotation of the hammer by the driver, and valve means effecting the exhaust of pressure fluid from said chamber operative as an incident to the interruption of rotation of the hammer by the driver.

3. In a rotary impact tool, a clutch mechanism comprising, in combination, a rotary anvil, a hammer rotatable relative to the anvil and shiftable axially into and out of driving engagement with the anvil, a driver, and means for effecting the engagement and disengagement of the hammer element with respect to the anvil comprising a diaphragm of resilient material connecting the driver with said hammer and coacting therewith to form a pressure chamber, an air supply passage, means for supplying air under pressure to said chamber during the rotation of the hammer by the driver, and valve means effecting the exhaust of pressure fluid from said chamber operative as an incident to the interruption of rotation of the hammer by the driver, said valve means comprising a part associated with the hammer and a part connected with the driver for movement thereby relative to the hammer part.

4. An impact clutch comprising, in combination, rotary anvil and hammer elements relatively shiftable into and out of driving engagement, means for driving the hammer element, and means for effecting the engagement and disengagement of said elements including a pressure chamber associated with one of said elements, means for admitting fluid under pressure to said chamber to effect a relative shift of said elements into driving engagement, and a valve device operative to cause the intermittent exhaust of pressure fluid from said chamber whereby to initiate a corresponding shift of said elements out of driving engagement.

5. An impact clutch having, in combination, coaxial anvil and hammer elements mounted for relative axial shifting movement, means for driving the hammer element, means for effecting the intermittent engagement and disengagement of said elements including a pressure chamber having a resilient wall providing a driving connection between the hammer element and said drive means, means for introducing pressure fluid into said chamber to effect a relative shift of said elements in one direction, and means for intermit-

tently exhausting the pressure fluid from said cylinder to effect a relative shift of the elements in the opposite direction.

6. A rotary impact tool comprising, in combination, a rotary driver, a hammer element, a diaphragm resiliently connecting the hammer element with the driver and coacting with the hammer element to form a pressure chamber, a rotatable anvil element, said hammer and anvil elements having coacting jaws and the two elements being relatively shiftable to effect engagement and disengagement of said jaws, means for admitting fluid under pressure to said chamber to effect the engagement of said jaws, and valve means operative upon interruption of rotation of the hammer element by the anvil to permit escape of fluid pressure from said chamber and thereby effect the disengagement of said jaws.

7. A rotary impact tool comprising, in combination, a rotary driver, a hammer, a diaphragm resiliently connecting the hammer with the driver and coacting with the hammer to form a pressure chamber, a rotatable anvil, said hammer and anvil having coacting jaws and being relatively shiftable to effect engagement and disengagement of said jaws, means for admitting fluid under pressure to said chamber to effect the engagement of said jaws, and valve means operative upon interruption of rotation of the hammer by the anvil to permit escape of fluid pressure from said chamber and thereby effect the disengagement of said jaws, said valve means comprising a part rotatable with the hammer and a part rotatable with the driver so as to be shiftable relative to the hammer part when rotation of the latter is interrupted.

8. In a rotary impact tool, the combination of a rotary anvil, a rotary hammer shiftable into and out of driving engagement with the anvil, a spring tending to hold the hammer out of engagement with the anvil, fluid pressure operated means for effecting the engagement of the hammer with the anvil, and valve means controlling the disengagement of the hammer from the anvil.

9. In a rotary impact tool, the combination of a rotary anvil, a rotary hammer shiftable into and out of driving engagement with the anvil, a spring tending to hold the hammer out of engagement with the anvil, and fluid pressure operated means for effecting the engagement of the hammer with the anvil including a pressure chamber, and a valve device comprising a part actuated by the driver and rotatable relative to the hammer, a part carried by the hammer and means for limiting the extent of relative rotation between said valve parts.

10. In a rotary impact tool, the combination of a rotary anvil, a rotary hammer shiftable into and out of driving engagement with the anvil, a spring tending to hold the hammer out of engagement with the anvil, fluid pressure operated means for effecting the engagement of the hammer with the anvil including a pressure chamber, and valve means operative to intermittently close and vent said chamber whereby to alternately increase and decrease the pressure in said chamber for shifting said hammer into and out of driving engagement with said anvil.

11. An impact clutch comprising, in combination, rotary anvil and hammer elements relatively shiftable axially into and out of driving engagement, a driver, a resilient connection between the driver and the hammer element permitting of relative rotation of the hammer element with respect to the driver, said hammer

having a pressure area, and means for intermittently subjecting said area to fluid pressure whereby to cause movement of the hammer into engagement with the anvil.

12. In a rotary impact tool, in combination, coaxial anvil and hammer elements mounted for relative axial shifting movement into and out of driving engagement, a rotary driver, a resilient member providing a driving connection between said driver and said hammer element and defining one wall of a pressure chamber, means for introducing pressure fluid into said chamber to effect a relative axial shifting of said elements in a direction to establish a driving engagement therebetween, said member yielding in a circumferential direction to permit relative rotational movement of the hammer element and said driver when a predetermined resistance is opposed to the rotation of the anvil element, and valve means operative upon such relative rotation for venting said chamber to effect a relative axial shifting of said elements in a direction to interrupt the driving engagement between the elements.

13. In a tool of the class described, in combination, coaxially arranged driving and driven elements supported for relative axial and rotational movements, a resilient member providing a driving connection between said elements and defining with said driven element a pressure chamber, means for introducing pressure fluid into said chamber to effect a relative axial shifting of said elements in one direction, said resilient member acting normally to hold said elements in predetermined angular relationship and yielding in a circumferential direction to permit relative rotation of the elements when a predetermined

resistance is opposed to the rotation of said driven element, and means operative upon such relative rotation of the elements or venting said chamber to effect a relative axial movement of the elements in the opposite direction.

14. In a rotary impact tool, in combination, coaxially arranged anvil and hammer elements relatively shiftable axially into and out of driving engagement, a rotary driver, means operatively connecting said driver and said hammer element, pressure fluid actuated means operative to relatively shift said elements and maintain them in driving engagement, said connecting means permitting limited rotational movement of said hammer element relative to said driver when a predetermined resistance is opposed to the rotation of said anvil element, and valve means operative incident to said relative rotation of said hammer element and said driver for rendering said pressure fluid actuated means ineffective to maintain said elements in driving engagement.
